**ITIVE PHOTOGRAPHIC
ELEMENT**

René Adriaan Stevens, Antwerp, Laurent Aloys Van Der Auwera, Mortsel-Antwerp, and Désiré Maria Aloysius Van Goethem, Kontich, Belgium, assignors to Gevaert Photo-Producten N. V., Mortsel-Antwerp, Belgium, a company of Belgium.

**No Drawing. Application April 15, 1947, Serial
No. 741,684. In Germany April 22, 1942**

Section 1, Public Law 690, August 8, 1946
Patent expires April 22, 1962

3 Claims. (Cl. 95—8)

1

This invention relates to colored photographic layers, especially filter and anti-halation layers having no binding agent, and to a process for manufacturing the same.

Anti-halation layers have to meet the following requirements: their absorptive power should be adapted to the optical sensitivity of the silver halide emulsions; they should lose color quickly, completely and irreversibly in weak alkaline developing baths; and their decomposition products should exert no influence on the development or on the photographic properties of the emulsion. The layers should also withstand mechanical influences which remove the dyestuff itself or which could damage the thin layer.

The known anti-halation layers meet only one of the above listed requirements, that is to say, it is known to use irreversibly discoloring anti-halation layers characterised by the presence of condensation products of substituted aromatic aldehydes with quaternary heterocyclic bases containing a reactive methyl group. Condensation products of equimolar quantities of aromatic or cyclic aldehydes with cyclic combinations containing a reactive methylene group, or condensation products of dehydracetic acid with aromatic aldehydes and ketones, respectively, have also been used for the same purpose.

In order to obtain the desired resistance of the layers, the use of synthetic resins as binding agents for the dyestuff, or the varnishing of the layer with natural or synthetic resins containing at least one self-forming hydroxyl or carboxyl group and being soluble in alkaline baths, has been proposed.

It is among the objects of our invention to generally improve colored photographic layers, particularly to provide filter and anti-halation layers having several of the above mentioned properties simultaneously.

A further object of our present invention is to provide a photographic light-sensitive single or multi-layer silver halide material containing at least one of the said colored photographic layers.

To the accomplishment of the foregoing and
other more detailed objects which will herein-
after appear, our invention consists in the prod-
uct and the method of producing same, as here-
inafter are more particularly described in the
specification and sought to be defined in the
claims

In accordance with our invention, colored photographic layers are manufactured by using salts of organic acids containing at least one salt-forming COOH or OH group and of azo-

2

methine dyestuffs of the type that is obtainable as, for instance, by condensation of substituted or unsubstituted aliphatic, aromatic or heterocyclic aldehydes with suitable substituted anilines or amines, preferably in equimolar quantities.

By using these salts, the color intensity of the dyestuffs is considerably increased. Additionally, the unexpected fact has been noticed that these dye salts produce intense dyestuffs which dis-
color irreversibly in weak alkaline developers and also possess the property of forming an intensively colored varnish layer from an aqueous or
alcoholic solution without the use of a binding
agent.

For the manufacturing of the azomethine dye-stuffs the following amines may be used:

20   ortho-amidobenzoic acid,
       amidosalicyclic acid,
       para-amidobenzoic acid,
       benzidin,
       para-anisidin,
       para-amidodiphenylamine,
       ortho-anisidin,
       para-toluylediamine,
       xylidin,
       dibromoanthranilic acid,
       aminophenylthiocarbamide.

30 Suitable aldehydes are, e. g., para-dimethylaminobenzaldehyde, vanillin, salicylic aldehyde, para-oxybenzaldehyde, para-dimethylaminocinnamic aldehyde.

35 Benzoic acid, hydroxybenzoic acid, methylene-disalicylic acid, methylenedigallic acid may, for instance, be used for the formation of the salts of the azomethine dyestuffs.

Some specific examples of the method of our invention are given hereinafter.

40

Example 1

1 mol anthranilic acid and 1 mol para-dimethylaminobenzaldehyde are heated in a diluted alcoholic solution. A colored combination separates immediately and is crystallised from alcohol

This azomethine dye base is condensed in equimolar proportions with methylenedisalicylic acid in alcohol.

3

Example 2

1 mol anisic aldehyde is condensed as in Example 1 with 1 mol amidodiphenylamine to an azomethine dyestuff of the following probable structure

This azomethine dye base is condensed in equimolar proportions with salicylic acid in alcohol. 10

Example 3

1 mol para-dimethylaminocinnamic aldehyde is condensed in the same way with 1 mol ortho-aminobenzoic acid and afterwards converted to 15 dye salt by means of methylenedisalicylic acid

All of the above dyestuffs are suitable for all photographic purposes where a layer discolorable in a weak alkaline medium is required, as e. g. for filter layers, anti-halation layers, back layers, and also for direct addition to the silver halide emulsion. 25

It is believed that the general method and the specific examples of our invention, as well as the advantages thereof, will be apparent from the foregoing detailed description. It will also be apparent that while we have shown and described preferred examples of our invention, changes may be made without departing from the spirit of the invention, as sought to be defined 35 in the following claims.

We claim:

1. Photographic material containing at least one light-sensitive silver halide emulsion layer and a colored non-sensitive layer including the 40 reaction product of a basic azomethine dyestuff, obtained by condensing in equimolar proportions an aldehyde selected from the group consisting of p-dimethylaminobenzaldehyde and p-dimethylaminocinnamic aldehyde, and anthranilic acid, with methylene disalicylic acid, said reaction product corresponding to the following formula:

wherein A represents the atoms necessary to complete with H benzoic acid, B represents the atoms necessary to complete with OH— an aldehyde selected from said group of aldehydes, R represents the atoms necessary to complete with H methylene disalicylic acid, the radical of the latter acid being linked to the N-atom so that 50

4

the salt-forming OH remains intact, and n represents a positive integer of from 1 to 2.

2. Photographic material containing at least one light-sensitive silver halide emulsion layer and a colored non-sensitive layer including the dyestuff of the formula:

3. Photographic material containing at least one light-sensitive silver halide emulsion layer and a colored non-sensitive layer including the dyestuff of the formula:
